Sam'l F. Shadbold, Inventor.

United States Patent Office.

SAMUEL F. SHADBOLT, OF HUNTINGTON, NEW YORK.

Letters Patent No. 72,548, dated December 24, 1867; antedated December 12, 1867.

IMPROVED VALVE-STOPPER FOR JARS, BOTTLES, &c.

The Schedule referred to in these Letters Patent and making part of the same.

TO ALL WHOM IT MAY CONCERN:

Be it known that I, SAMUEL F. SHADBOLT, of the town of Huntington, in the county of Suffolk, and State of New York, have invented a new and improved Valve-Stopple; and I do hereby declare that the following is a full and exact description thereof, reference being had to the accompanying drawings, and to the letters of reference marked thereon.

Figure 1 is a plan view of the valve-stopple separate from the bottle D, as seen in figs. 2, 3, and 4.

Figure 2 is an end view of the bottle D in figs. 3 and 4.

Figure 3 is a side elevation, D the bottle, E the collar, b b the wire, B the arm or shaft.

Figure 4 is a cut section of fig. 3.

The nature of my invention consists in providing the upper part of a neckless bottle, or its equivalent, with a rubber valve or stopple attached to a shaft, and secured to the top of the bottle in a groove which allows the shaft to which the valve or stopple is attached to oscillate freely, thus opening and shutting the bottle as force is applied to the inner lower surface of the rubber valve by the gaseous contents of the bottle within or by turning the handle of the shaft to which the rubber valve is attached from without.

To enable others skilled in the art to make and use my invention, I will proceed to describe its construction and operation.

The bottle to which my valve-stopple may be applied is made of glass, or of any other material of which bottles are or may be made, and in the same manner, and in any desirable shape, but without necks. The diameter of the mouth of the bottle is made about three-fourths of that of the diameter of the top of the bottle, which is made slightly convex. Around the mouth of the bottle I cut the small groove F, in which I place a wire, or its equivalent, which, passing over the ends of the shaft B, to which the rubber valve is attached, holds it firmly in its place, while allowing the shaft to oscillate freely when force is applied to it. Across the mouth of the bottle, at either side of the centre, I cut a groove, in which the shaft to which the rubber valve is attached is placed, as seen at G, figs. 2 and 4. I make my valve or stopple of a piece of rubber, or its equivalent. I make it a little larger than the mouth of the bottle, and of the same shape, so that when forced up against the under side of the mouth, it completely and hermetically closes the orifice. This rubber valve A is attached in the centre to the projection C of the shaft B by the rivet a, as seen at figs. 1 and 2; the shaft B, with the rubber valve attached, being placed in the groove G and secured by the wire b passing around in the groove F. The gaseous liquid is introduced by opening the rubber valve by the handle, which, when left go, closes tightly on the under side of the mouth of the bottle, partly by the elasticity of the rubber valve, which in opening is pressed against the side of the bottle, and partly from the force of the gaseous contents of the bottle. Should the elasticity of the rubber valve be insufficient to close the orifice tightly, when the contents of the bottle are not of a gaseous nature, a rubber band, fastened to the handle and to a knob on the side of the bottle, may be used, as seen at H, fig. 3, or by a.

The advantages of my valve-stopple are, first, it being easily detached from the bottle, and the mouth being wide, without a neck, the bottle is more easily cleaned than other bottles; second, it being self-acting, saves the cost of corks and the labor of corking and wiring, also prevents insects and dirt from getting into the bottles when empty; third, the contents of the bottle are more easily and quickly emptied than any now in general use; fourth, the valve being securely fastened, there is no possibility of the gas forcing it out, while the bottle is less liable to break in the process of corking, as is frequently the case in corking bottles containing gaseous liquids; fifth, it is more easily opened in pouring out the liquid, and can be held in any position.

What I claim, and desire to secure by Letters Patent, is—

A valve-stopple for bottles, composed of rubber, or its equivalent, attached to a shaft, substantially as described and for the purpose set forth.

SAM'L F. SHADBOLT.
